R. W. MANEVAL

ATTACHING MEANS FOR BOX LIDS

Filed June 19, 1926

INVENTOR.

REX W. MANEVAL

BY

E.G. Charles

ATTORNEY.

UNITED STATES PATENT OFFICE.

REX W. MANEVAL, OF FRANKFORT, KANSAS.

ATTACHING MEANS FOR BOX LIDS.

Application filed June 19, 1926. Serial No. 117,111.

My invention relates to an attaching means for box lids.

The object of my invention is to provide an attaching means that will fasten the lid 5 firmly to the box without the use of tools.

A further object of my invention is to provide an attaching means that tends to strengthen the box.

A still further object of my invention is to 10 provide an attaching means eliminating the driving of nails and removal of same, both of which cause unusual jar of the contents of the box.

A still further object of my invention is to 15 provide an attaching means preferably for egg crates.

A still further object of my invention is to provide a simple and effective means to hold the lid on a box in such a way as not to damage 20 the material thereof, whereby a repeated use may be had.

These and other objects will hereinafter be more fully explained.

Referring to the drawings:

25 Fig. 1 is a perspective view of a box showing the application of the attaching means.

Fig. 2 is an enlarged end view of the device.

Fig. 3 is a top view of the device.

30 Fig. 4 is an inverted or bottom view of Fig. 3.

The mechanism herein disclosed functioning as a box lid attaching means is preferably applied to egg crates, and by which means undue jar of the contents thereof is 35 eliminated by the non-usage of nails. I do not confine the device to be used on egg crates alone as the same would be found valuable in crates for glass jars, canned fruit 40 or other commodities of like character where heavy strokes from a hammer may prove disastrous; and furthermore a lid may be securely fastened in very much less time than the former way of nailing. The time 45 required for the removal is equally shortened and the lid may be used many times as heretofore stated which is further economy.

In Fig. 1, 2 is a box having a lid 3, the said box being constructed as an egg crate 50 having cleats 4 and 4' on the ends thereof. The said cleats being placed to bind the members of the end together and simultaneously affording a better nailing edge for the bottom and the top.

55 With my newly invented attaching means, the nailing of the lid is eliminated, but the

cleat is employed as hereinafter described. The attaching means consists of a strip of metal 5 being bent to a right angle as shown at A, and having a plurality of V-shaped cuts 6 distributed along the plane thereof. The said cuts when turned downward as shown in Fig. 2 function as spurs to be forced into the lid to prevent sliding therefrom. 65

Along the opposite edge of the member 5 is a series of teeth 7 which are bent at right angles as shown at B, and the points thereof having a return bend as shown at C in Figs. 2 and 4; the object of which is that the 70 points will engage snugly between the cleat 4' and the end of the box as shown at D in Figs. 1 and 2. The position of the cleat, the lid and the box are shown by dotted lines in Fig. 2. 75

The mechanism herein disclosed is preferably made of sheet metal, the gauge of which will be equal to the tension required for securely attaching the lid to the box. At the same time resiliency is preferred so that the 80 member extending over the top of the lid will tension firmly thereto as the spurs enter the wood. Note that the spurs angle toward the end of the box so that an outward thrust by a stroke on the edge as shown 85 at E in Fig. 1 would tend to imbed the spurs more firmly in the wood preventing an outward rocking of the structure releasing it from its function.

The plane of the structure having the 90 spurs formed therein is of sufficient width that a thin pointed instrument may enter between the edge thereof and the lid causing it to spring upward, by which means the spurs may be withdrawn, and the attaching means rocked outward to disengagement. In other words sufficient leverage is 95 acquired by the edge extending over the lid to a liberal distance, and the spurs being centrally positioned, renders the easy removal thereof by the application of a similar instrument as above mentioned.

The points of the teeth imbedding into or back of the cleat is a feature that will prevent the attaching means simultaneously 105 with the spurs from sliding longitudinally.

Such modifications may be employed as lie within the scope of the appended claims.

Having thus described my invention, what I claim as new and desire to secure by Letters Patent is:—

1. In an attaching means for box lids, in

combination with a box having cleats on the ends thereof and a loosely positioned lid thereon, a metal structure having a right angle bend longitudinally to engage the full width of the lid, a plurality of spurs spaced along one leg of the structure to engage in the lid, a plurality of teeth laterally extending from the opposite edge of the structure to engage with the lower edge of the cleat as the rocking point for the strip when applied.

2. In an attaching means for box lids, in combination with a box having cleats on the

ends thereof and a lid to lap over the cleat, a metal strip having a right angle bend longitudinally, a plurality of V-shaped cuts centrally spaced along one leg of the strip, the points being bent to an angle from the plane of the leg functioning as spurs and being integral with the strip, a plurality of teeth on the opposite edge of the strip, the points of the teeth having a bend to engage at the joint between the cleats and the box, all as, and for the purpose described.

REX W. MANEVAL.
